J. F. MYERS.

ATTACHMENT FOR RANGES.

No. 471,222.

Patented Mar. 22, 1892.

THE NORRIS PETERS CO., PHOTO-LITHO., WASHINGTON, D. C.

UNITED STATES PATENT OFFICE.

JOHN F. MYERS, OF SAN FRANCISCO, CALIFORNIA.

ATTACHMENT FOR RANGES.

SPECIFICATION forming part of Letters Patent No. 471,222, dated March 22, 1892.

Application filed August 13, 1891. Serial No. 402,521. (No model.)

To all whom it may concern:

Be it known that I, JOHN F. MYERS, a citizen of the United States, residing at San Francisco, in the county of San Francisco and State 5 of California, have invented certain new and useful Improvements in Attachments for Ranges; and I do hereby declare the following to be a full, clear, and exact description of said invention, such as will enable others 10 skilled in the art to which it most nearly app- pertains to make, use, and practice the same.

My invention has relation to certain new and useful attachment for ranges, &c., which consists in the arrangement of parts and de- 15 tails of construction, as will be hereinafter more fully set forth in the drawings and de- scribed and pointed out in the specification.

The object of my invention is to provide an attachment for ranges, having secured thereto 20 an oven and broiler adapted to be secured to one end of the range and have connected thereto a series of gas-burners, thereby allowing of the ordinary range being utilized with gas or coal, or both together, thus not only 25 securing greater cooking room, but at the same time obviating the necessity of building a coal fire within the range for the purpose of preparing a slight meal, or the annoyance of having to wait a long while for the fire to 30 start when it is required to hastily heat water or prepare small dishes. The value and im- portance of the attachment in connection with ranges will be readily apparent to those fa- 35 miliar with the trouble and disadvantage of building and waiting for fire to burn in a range when preparing an early breakfast.

Referring to the drawings forming a part of this specification, wherein similar letters of reference denote corresponding parts through- 40 out the entire specification and several views, Figure 1 is a perspective view showing attachment secured to an ordinary coal-range; Fig. 2, a detached view of attachment, show- 45 ing oven and broiler secured thereto; Fig. 3, a detail view showing removable range-shelf with oven and broiler removed therefrom; and Fig. 4, a sectional view on line $x-x$, Fig. 2.

The letter A is used to indicate an ordinary coal-range, which is provided with the end 50 lugs or projections a.

The removable supporting-shelf is repre-

sented by the letter B, which is provided with the back openings b, through which lugs a pass, thus securing or holding the shelf firmly to the range. Beneath said shelf is located 55 the gas-burners C, the flame from which is adapted to extend through the cut-away por- tion c of the shelf.

Cooking utensils rest upon the shelf directly over the flame, so as to receive all possible 60 heat.

Secured to and depending from shelf B are supports or arms D, to which is secured oven D'. This oven may be constructed of any suitable material, preferably sheet-iron, pro- 65 vided with sheet or cast iron bottom d, to which is secured broiler-oven E. Within said broiler is located burner E', and communica- 70 tion is made from the broiler to oven D' by means of openings d', formed in bottom d of the oven, thus allowing of heat from the broiler passing into oven.

The broiler-oven is adapted to hold broiler and drip-pan E² E³, as shown. If so desired, the oven and broiler may rest upon the shelf 75 instead of depending therefrom.

The gas-supply pipe for the burners is shown by letter F, which is provided with stop-cocks e for the purpose of regulating the flow of 80 gas or flame of burner.

By constructing the shelf with depending arms the baking and broiler ovens may be allowed to fit snugly against the range without damage, which would follow in case the same had to be bolted thereto. 85

Inasmuch as the supporting-shelf is remov- ably attached to the range, the whole may be quickly detached with little or no trouble, thus dispensing with the gas-oven and allowing the range to be used as an ordinary coal 90 one.

This attachment will be found of the utmost importance in connection with coal- ranges whenever it is desired to prepare only slight meals or where it is necessary to quickly 95 heat food for invalids, &c.

Having thus described my invention, what I claim as new, and desire to secure protec- 100 tion in by Letters Patent of the United States, is—

The combination, with a stove having lugs a on its upper side at its rear end, of a shelf

provided with slots engaging the said lugs, burners supported by and beneath the said shelf, hangers secured to and depending from the shelf, a cooking-oven secured to the hang-
5 ers, a broiler-oven supported by and below the cooking-oven, and burners within the broiler-oven.

In testimony whereof I affix my signature in presence of two witnesses.

JOHN F. MYERS.
